UNITED STATES PATENT OFFICE.

DON N. THOMPSON, OF SYRACUSE, NEW YORK, ASSIGNOR TO PASS & SEYMOUR INC., OF SOLVAY, NEW YORK, A CORPORATION OF NEW YORK.

SUPPORT CONSTRUCTION FOR ELECTRICAL APPLIANCES.

Application filed May 9, 1924. Serial No. 712,032.

This invention has for its object a particularly simple, light and strong construction of supports for electrical appliances, as lamp sockets, etc., by which the sockets or other appliances are connected to a supporting fixture, or to any other support. The invention consists in the novel features and in the combinations and constructions hereinafter set forth and claimed.

10 In describing this invention reference is had to the accompanying drawings, in which like characters designate corresponding parts in all the views.

15 Figure 1 is a sectional view, partly in elevation, of a lamp socket support embodying this invention.

Figure 2 is an inner face view of the support, the contiguous portion of the casing being also shown.

20 Figure 3 is a detail view of the ring to which the appliance is attached by screws.

Figure 4 is a detail sectional view partly broken away of the ring member and nipple.

This support comprises generally a nipple, 25 a ring member 1 to which the appliance is secured, the ring member having means for interlocking with the nipple to prevent relative turning of the nipple and the ring.

2 is the nipple, it being usually internally threaded for receiving a threaded supporting fixture or for receiving a bushing through which the feed wires pass, the nipple having a peripheral groove 3 at its inner end, and a notch 4 which intersects the 35 groove.

5 is the ring member interlocked with the nipple, it having its inner edge or margin located in the groove 3, and having a tongue 6 which extends into the notch 4. The ring 40 member 5 is usually flat. As here illustrated the nipple is formed with a reduced portion or lip 7 in its inner end, and the margin of this reduced portion or lip is

spread or spun over at 7^a on the lower face of the ring, and thus forms the groove 3. 45

Usually in lamp socket constructions the ring member is covered by an annular convex sheet metal plate A, formed with an annular shoulder at 8 against which the outer margin of the ring 5 abuts, and the inner 50 upper edge of the sheet thrusts against an annular peripheral shoulder 9 on the nipple.

The ring member 5 is also formed with one or more threaded openings 10, which receive the screws 11, by which the lamp socket or 55 the base 12 thereof is secured to the cap.

Owing to the tongues 4 interlocking with the nipple, turning of the socket or other appliances and the ring member 5, relatively to the nipple is prevented and hence twisting of the feed wires passing through the nipple, and breaking of the joints between the feed wires and the wire terminals of the lamp socket is prevented. 60

What I claim is:

A support construction for electrical appliances comprising a nipple formed with an annular, peripheral groove at its inner end, and with a notch intersecting the groove, and also with a shoulder above and 70 spaced from the groove, a ring member having its inner margin extending into the groove of the nipple and a tongue extending into the notch, the ring member being formed with threaded openings for receiving the fastening screws of the appliance, a sheet metal shell in the form of a canopy having its upper end thrusting against said shoulder and being formed between its ends with a shoulder thrusting against the upper 75 face of the ring member. 80

In testimony whereof, I have hereunto signed my name at Syracuse, in the county of Onondaga, and State of New York, this 1st day of May, 1924.

DON N. THOMPSON.
